ELECTRIC IGNITERS FOR USE WITH FLUENT FUEL BURNERS AND IN SPARKING PLUGS

Thomas F. Dryden, London, England, assignor to The Babcock & Wilcox Company, New York, N.Y., a corporation of New Jersey

Application May 10, 1955, Serial No. 507,287

6 Claims. (Cl. 317—83)

This invention relates to electric igniters for use with fluent fuel burners and to sparking plugs and to a method of manufacture of such sparking plugs. The methods of lighting up commonly used in small furnace chambers fired with fluent fuel are unsuitable for application to large furnace chambers such as those found in modern central station boilers and the practice has arisen of utilising automatic apparatus for effecting lighting up. Such apparatus involves electrical ignition means and in order to obtain the necessary energy in the spark a high tension of some thousands of volts has commonly been employed. In such a high voltage system the insulators are prone to breakage or to failure due to dirty surfaces. In addition danger to personnel may arise. An object of the invention is the provision of an improved relatively low voltage ignition system for effecting ignition in a furnace chamber.

In order to be effective, the electrodes of an ignition system must be properly positioned in relation to the stream of fluent fuel to be ignited, but when the spark has effected ignition of the burner with which the system is associated, the electrodes are usually withdrawn from the heat of the flame. If the burner itself is an ignition burner for a pulverised fuel fired furnace, the burner as a whole must be withdrawn at the termination of the lighting up period. In some forms of burner a circular series of air directing vanes is provided adjacent the burner tip and the electrodes must be projected beyond the vanes in order to ignite the burner and then withdrawn behind the vanes and a further object of the invention is the provision of an igniter in which this may be accomplished by a simple linear movement of the electrodes and without making a large aperture in the vanes.

A still further object of the invention is the provision of a simple but effective form of sparking plug including a surface adapted during operation to be traversed by spark discharges and an economical method of manufacture of the plug.

The present invention includes an electric igniter for use with a fluent fuel burner comprising a sparking plug arranged to be projected to and retracted from an operative position and comprising an inner electrode and an outer electrode surrounding the inner electrode, separated therefrom by insulating material and extending in or substantially in the direction of movement between the projected and retracted positions, the insulating material providing an annular surface disposed at the forward end of the outer electrode between that electrode and the inner electrode and adapted, during operation of the plug, to be traversed by spark discharges between the electrodes.

The invention also includes a sparking plug having an inner electrode, an outer electrode of tubular form surrounding the inner electrode and separated therefrom by insulating material which affords an annular surface disposed between the electrodes at one end of the outer electrode and adapted, during operation of the plug, to

be traversed by spark discharges between the electrodes, at least an end portion of the insulating material adjacent the annular surface being compressed between the electrodes.

5 The invention further includes an electric igniter for use with a fluent fuel burner comprising a sparking plug arranged to be projected to and retracted from an operative position, a capacitance, an electric charging circuit for the capacitance and an electric discharge circuit including in series the capacitance, the sparking plug and a switch arranged periodically to close the discharge circuit.

10 The invention moreover includes the method of forming a sparking plug which includes assembling an inner rod electrode member within a tubular outer electrode member with insulation between the members and swaging the outer electrode member and thereby compressing insulating material between the electrode members, firmly uniting the electrode members and reducing the 15 diameter of the end of the outer electrode member bounding the annular surface which is afforded by the insulation at one end thereof and is adapted, during operation of the plug, to be traversed by spark discharges between the electrodes.

15 The invention will now be described, by way of example, with reference to the accompanying drawings, in which:

Figure 1 is a longitudinal sectional elevation to a relatively large scale, of a sparking plug;

20 Figure 2 is a longitudinal sectional elevation of an electrically-operated igniter assembly which includes the sparking plug of Figure 1;

25 Figure 3 is a partly diagrammatic, sectional side view of an oil burner in its operative position, the oil burner, certain parts of which have been omitted, constituting an ignition burner for a pulverised fuel fired furnace and employing the igniter shown in Figure 2;

30 Figure 4 is a sectional plan view at right angles to Figure 3 the burner being shown in this view in its retracted position;

35 Figure 5 is a sectional view illustrating a detail of the burner and taken on the line V—V of Figure 3;

40 Figure 6 is a fragmentary sectional view of a detail of the burner taken on the line VI—VI of Figure 4; and

45 Figure 7 is a schematic view of electrical circuit means associated with the igniter assembly.

Referring to Figure 1, a sparking plug 1 for use in an electric igniter of an oil fired burner constituting an ignition burner for a pulverised fuel fired furnace, includes an inner electrode 3 in the form of a cylindrical mild steel rod having a diameter of $\frac{5}{32}$ inch and a length of $5\frac{3}{4}$ inches which is disposed within an outer, co-axial tubular, mild steel electrode 5 having an overall diameter of $\frac{1}{16}$ inch, a thickness of 0.031 inch and a length of $4\frac{11}{16}$ inches. The forward end of the electrode 3 extends a distance of $\frac{3}{16}$ inch beyond the forward end of the electrode 5 from which end a tube 7 of mica mounted in closely fitting relationship upon the inner electrode 3 and made from sheet mica of 0.015 inch thickness extends rearwardly for about 1 inch and is compressed over a forward section 9 thereof between the electrodes 3 and 5. To this end the diameter of a forward end portion 11 of the electrode 5, which portion is about $\frac{1}{2}$ inch long, is reduced by swaging of the outer electrode 5 over the said portion 11 thereby compressing the forward section 9 of the tube 7 between, and firmly uniting the electrodes 3 and 5. At its forward end the mica tube 7 provides an annular surface 13 which, during operation of the plug, is traversed by spark discharges between the electrodes 3 and 5. The thickness of the tubular electrode

5 is so selected that, during operation of the plug, erosion of that electrode takes place at a rate which is approximately the same as that at which the mica tube 7 is eroded. Thus any tendency for an annular gap to appear, during operation of the plug, between the electrodes 3 and 5 rearwardly of the forward end of the electrode 5 is reduced thereby rendering the spark discharges between the electrodes effective to promote ignition over the full length thereof.

Around its rear end the tubular electrode 5 is provided with a closely fitting, mild steel ring 15 which is soldered to the electrode 5 and includes a rear portion 17 of uniform external diameter and a front, forwardly tapering portion 19. Mounted upon the inner electrode 3 rearwardly of the electrode 5 is a bushing 21 of asbestos cement insulating material and including a forward section 23 of reduced external diameter which fits within the rear end of the tubular electrode 5 and a rearward section 25 which has an external diameter equal to that of the ring portion 17 and, at its forward end, provides a shoulder 27 which is held against the rear end of the electrode 5 and ring 15 by means of a nut 29 which engages a rear, externally threaded end part 31 of the electrode 3.

The sparking plug 1 is formed by mounting upon and soldering to the electrode 5 the ring 15, locating the mica tube 7 upon the electrode 3, arranging the electrode 3 in position within the electrode 5 swaging the forward portion 11 of the electrode 5 down upon the tube 7 thereby compressing the tube 7 between and firmly uniting the electrodes 3 and 5, threading the bushing 21 onto the rear end of the electrode 3 and tightening up the nut 29 to fix the bushing 21 in position.

The electrodes 3 and 5 are cut from stock material so that the labour involved in their manufacture is minimised. It will be observed that the swaging is restricted to the forward end portion 11 of the outer electrode 5 so that the work required in forming the plug is minimised and the full diameter of the electrode 5 is available between the swaged portion and the rear end of that electrode, a feature which makes for improved rigidity of the plug under operating conditions.

The sparking plug 1 which somewhat resembles a long pencil is readily replaceable in relation to a reciprocable holder 33, shown in Figure 2, which is associated, in a manner hereinafter described, with pneumatic means for effecting the reciprocating movement in relation to an associated oil burner which constitutes the ignition burner for a pulverised fuel fired furnace, the ignition burner itself being movable between a projected operating position and a refracted position.

The holder 33 comprises a mild steel, tubular member 35 having an internal diameter which is slightly greater than the external diameter of the ring 15 and the bushing 21 and within the forward end of which is welded a ring member 37, the latter including a forward section 39 which fits upon the tubular electrode 5 and a rearward section 41 the inner surface of which is complementary with and engages the forwardly tapering surface of the portion 19 of the ring 15. A rear end portion 43 of the tubular member 35 is welded within a forward section 45, of reduced internal diameter, of a tubular part 47, having a rear section 49. The tubular part 35 provides a housing for a resilient electrical terminal device 51 which is spring-biased to a forward position in which it is urged into contact with the rear end 31 of the electrode 3 in the manner described below.

The terminal device 51 comprises a rod 53 having a diameter approximately equal to that of the electrode 3 and extending axially within the tubular member 35, the rear end of the rod 53 projecting beyond the rear end of the tubular part 47 whilst upon the forward end of the rod 53 is mounted a bushing 55 formed from asbestos-cement insulating material and having a bore 57 a rearward section 59 of which is of reduced diameter and

10 closely fits the rod 53 whilst a forward section 61 of the bore 57 projects beyond the forward end of the rod 53 to provide a socket which accommodates a brass terminal member 63. The terminal member 63 includes a rearward ring-like part 65 which closely fits between the rod 53 and the bushing 55 and a forward, solid cylindrical part 67, the front surface 69 of which is rearwardly dished to provide a contact surface complementary with the adjacent end surface of the electrode 3.

15 Disposed within the tubular part 47 is a housing 69 for a coil spring 71 which is mounted on the rod 53. The housing is formed from resin-impregnated insulating material and comprises four annular elements 73, 75, 77 and 79. The forward element 73 of the housing 69 has a rearward part 81 which fits within the front end of the rear section 49 of the part 47 and a forward part 83 which engages within the rear end of the tubular member 35, the arrangement being such that an annular shoulder 85 formed at the front of the part 81 abuts a complementary shoulder 87 formed by the rear end surface of the tubular member 35 and the annular surface between the sections 45 and 49 of the part 47. A central bore 89 of the element 73 includes a forward portion 91 which fits the rod 53 so as to permit sliding of the rod therethrough and a rearward portion 93 of increased diameter. The elements 75 and 77 of the housing 69 have the same external diameter and engage within the section 49 of the tubular part 47, the internal diameter of each of the elements 75 and 77 being equal to that of the portion 93 of the element 73. The annular element 79 has an external diameter equal to that of the element 77 and fits within the end of the annular part 47. A central bore 95 of the element 79 includes a forward section 97 of diameter equal to that of the internal diameter of the elements 75 and 77 and a rearward section 99 co-axial with and of the same diameter as the bore portion 91 of the element 73.

20 For retaining the housing 69 within the tubular part 47 a union nut 101 is mounted upon an externally threaded end part 103 of the tubular part 47 and provides a radially inwardly extending annular flange 105 between which and the shoulder 87 are clamped the elements of the housing 69.

25 The rod 53 projects rearwardly beyond the flange 105 and has an externally threaded end portion 107 adapted for connection to an electrical supply.

30 The internal bores of the elements 75 and 77 and the bore portions 93 and 97 respectively of the elements 73 and 79 together constitute a cylindrical cavity 109 within which is disposed the coil spring 71 which is adapted to bias the rod 53 to a forward position. To this end the rod 53 is provided with a pin 113 which extends through the rod 53 normal to the axis thereof. Rearwardly of the pin 113 is provided a washer 115 mounted on the rod 53 and free to slide within the cylindrical cavity 109. The coil spring 71 is arranged in compression between the washer 115 and an annular shoulder 117 formed at the rearward end of the bore portion 97 of the element 79, the arrangement being such that rearward movement of the rod 53 places the spring 71 in greater compression.

35 Between the rod 53 and the tubular member 35, at suitable intervals along the length of the member 35 are provided porcelain insulators, such as the insulator 119, of annular form. It will be appreciated that the electrode 5, ring 15, ring member 37, tubular member 35 and tubular part 47 constitute an electrically conductive path and that the resilience of the spring 71 of the electrical terminal device 51 ensures that contact between the electrode 3 and the terminal member 63 is maintained notwithstanding differential expansion of the parts of the igniter which occurs during service thereof.

40 To assemble the plug 1 within the holder 33, the ring member 37 is welded within the forward end of the tubular member 35 and the tubular part 47 is mounted upon

the rear end of the member 35. The plug 1 is then inserted within the rear end of the tubular member 35 after which the rod 53, upon which are mounted the bushing 55, terminal member 63, insulators 119, housing element 73, pin 113 and washer 115, is inserted in the rear end of the tubular member 35 and moved forwardly to push the plug 1 through to its operative position at the forward end of the member 35. The housing elements 75 and 77 are then inserted within the tubular part 47, the spring 71 and housing element 79 are threaded on to the rear end of the rod 53 and urged forwardly until the element 79 is disposed within the rear end of the section 49 of the part 47 whereupon the union nut 101 is mounted on the threaded part 103 of the tubular member 47 and tightened up.

The plug 1 and holder 33 constitute an igniter assembly which, as shown in Figures 3, 4, 5 and 6 is utilised for effecting ignition in an oil-fired burner, generally indicated at 131, the burner being suitable for use as a starting burner for a pulverised fuel fired furnace. The burner 131 includes a mechanical, fuel atomizer unit 133 having a barrel 135 at the forward end of which is provided an atomizer head 137 and at the rear end of which are provided fuel supply means (not shown). The barrel 135 can be forwardly projected axially to an operative position and rearwardly retracted axially to a withdrawn position. For effecting such movement there are provided two double-acting air cylinders 143 and 145 mounted on the rearward side of an end plate 147 of the burner. The cylinders 143 and 145 which are disposed at the same horizontal level and on opposite sides of the barrel 135, are respectively provided with pistons (not shown) and connecting rods 149 and 151 which extend forwardly through apertures 153 and 155 in the plate 147 and at their forward ends are connected to a yoke 157 which is welded to a tube 159 within which the barrel 135 of the atomizer unit 133 is secured. The tube 159 and barrel 135 extend rearwardly through a sleeve 161 which is secured to the plate 147 by welding within a central aperture formed in that plate and constitutes a support within which the tube 159 slidably fits.

Towards its forward end the barrel 135 is secured to an inner, movable, tubular casing 163 of the burner by a support 165 in the form of a spider which includes vertically disposed lower and upper members 167 and 169 of which the lower member 167 extends between and is welded at its ends respectively to the inner surface of the casing 163 and a lower part of the barrel 135, whilst the upper member 169 is welded at its ends respectively to the inner surface of the casing 163 and an upper part of the barrel 135. The support 165 also includes two horizontally disposed members 171 respectively arranged on opposite sides of the barrel 135 and each having an inner end welded to the barrel 135 and an outer end welded to a vertical plate 173 which in turn is welded to the inner surface of the tubular casing 163.

The upper member 169 of the support 165 comprises two parallel plates 168 between which is welded an angle bracket 175 which serves, in a manner hereinafter described, as a forward support for the igniter assembly.

Around the atomizer head 137 is disposed a series of fixed vanes 177 arranged to impart a whirling motion to combustion air supplied, during operation, to the burner. The vanes 177 are connected at their outer edges to a sleeve 178 which is secured within the forward end of the casing 163.

The casing 163 is free to move with the unit 133 upon operation of the air cylinders 143 and 145. To this end there are provided in the horizontal diametrical plane of the casing 163, rollers 179 respectively mounted at opposite sides of the casing 163 and arranged to engage horizontal rails 181 provided upon diametrically opposite arcuate plates 183 which extend axially of the burner and are disposed outwardly of the casing 163, the plates

183 being welded at their forward ends to an annular support 185 surrounding the inner casing 163 and resting upon the inner surface of an outer tubular casing 187 of the burner provided with an inlet 188 for combustion air under pressure. The rails 181 extend rearwardly from the support 185 to a ring 189 which is provided with slots (not shown) for the passage therethrough of the plates 183. The ring 189 is formed around its periphery with a slot within which is disposed an asbestos gasket 191 for preventing, during operation of a furnace associated with the burner, rearward flow of hot gases between the inner and outer casings 163 and 187. The plates 183 at their rearward ends are connected by welding to inwardly extending projections 193 of an annular flange 195 which is disposed rearwardly of a flange 197 to which the rearward end of the outer casing 187 of the burner is welded.

A tubular casing 199 is provided at the rear end of the burner and includes at its front end a plate 201 formed with an aperture 203 through which the barrel 135 extends. The casing 199 is welded at its rear end to an annular plate 205 disposed rearwardly of the flange 195 and spaced therefrom by an asbestos gasket 207. The flanges 195 and 197, the gasket 207 and the plate 205 are secured by bolts 208 both to a rear wall 209 of a windbox for the burner and to the rear plate 147, the plate 205 being spaced from the plate 147 by cylindrical elements 211 the arrangement being such that all the parts of the burner within the casing 199 are exposed to atmospheric air and are thereby maintained cool. So as to prevent the flow into the interior of the casing 199 of combustion air which enters the burner through the inlet 188, there is provided around the barrel 135 adjacent the front plate 201 of the casing 199 a gland 213.

35 The igniter assembly which includes the plug 1 and holder 33 is secured within a tube 215 which extends rearwardly in a direction parallel with the atomizer unit 133 from a location adjacent the forward end of the holder 33. The tube 215 is supported towards its forward end within an aperture 217 formed in the bracket 175 and, rearwardly of the bracket 175, the tube 215 passes through an aperture 219 formed in the plate 201, there being provided a gland 221 for preventing rearward flow of combustion air through the aperture 219 into the casing 199. At its rear end the tube 215 passes through an aperture 223 formed in the plate 147. For effecting forward and rearward movement of the igniter there is provided a double-acting air cylinder 225 mounted at the rear side of the plate 147 and having, associated with a piston (not shown), a connecting rod which extends forwardly through an aperture in the plate 147 and is connected at its forward end to the tube 215 by means of a yoke 227.

55 As shown in Figure 3 with the atomizer unit 133 and the sparking plug 1 in their operative positions, the sparking plug extends through an aperture 229 formed in the vanes 177. In this position the forward end of the electrode 3 is arranged adjacent the surface of a conically shaped jet of atomized fuel indicated by the broken lines 231 which, during operation of the burner, is discharged from the atomizer head 137. It will be appreciated that the size of the aperture 229 is determined by the maximum diameter of the electrode 5 and that in view of the pencil-like form of the plug 1 an aperture of small diameter can be used so that in operation the symmetry of the air flow from the vanes is little disturbed and the shape of the flame from the burner is substantially unaffected.

60 The burner is provided with suitable doors (not shown) which are arranged during forward movement of the casing 163 to open and during rearward movement of the casing 163 to close. In their closed position the doors serve both to prevent flow of air forwardly through the casing 163 to the associated furnace chamber and to

protect the movable parts of the burner from radiation of heat from the furnace chamber.

To commence operation of the burner 131, air under pressure is supplied to the cylinders 143, 145 and 225 so as to project both the atomizer unit 133 and the igniter forwardly from the position indicated in Figure 4 to that indicated in Figure 3. As the igniter moves forwardly, electrical circuit means are operated and sparking of the plug 1 between the electrodes 3 and 5 and across the annular surface 13 commences. When the atomizer unit 133 reaches the position indicated in Figure 3, fuel oil under pressure is supplied thereto and the conical jet of atomized fuel discharged from the atomizer head 137 is ignited by the spark discharges between the electrodes of the sparking plug 1. Upon ignition of the atomizer fuel oil jet discharged from the head 137, the air cylinder 225 is operated so as to effect withdrawal of the sparking plug 1 through the aperture 229 in the vanes 177 to a position rearwardly of those vanes. The ignited fuel jet issuing from the atomizer head 137 is used to effect ignition of a jet or jets of pulverised fuel and air discharged from a burner or from respective burners disposed adjacent the burner 131 and, upon ignition of the pulverised fuel and air jet or jets, the supply of fuel oil to the atomizer unit 133 is cut off whereupon the cylinders 143 and 145 are operated to effect withdrawal of the unit 133 to the position indicated in Figure 4.

With a sparking plug such as that described above, the sparking always occurs across the annular surface 13 which is of small external diameter so that the region of sparking may be accurately located with respect to the conical oil jet discharged from the atomizer head 137 and may be intimately applied to that jet. Since the area of free movement of the spark is small the tolerance in the position of the sparking plug relatively to the oil jet in order to obtain reliable ignition is relatively great.

Electrical circuit means for effecting energisation of the sparking plug 1 are illustrated in Figures 6 and 7 which show the plug 1 connected in series with a capacitor 241 and switching device 243, the inner electrode 3 of the sparking plug being connected by way of the terminal and rod 53 to one side of the switching device 243, whilst the electrode 5 of the sparking plug is connected by way of the electrically conductive path including the ring 15, ring member 37, tubular member 35 and tubular part 47 of the igniter to the positive side of the capacitor 241 which side is maintained at earth potential. The capacitor 241 which has a capacitance of 12 micro-farads is further arranged in series with a charging circuit comprising a voltage doubler unit 247, which is arranged to be energised by a transformer 249 supplied from a low tension, alternating current source 251 of voltage 250 volts R.M.S. and frequency 50 cycles per second, and a pre-set resistor 245 which is adjusted to a value between 500 and 1,000 ohms to produce a charging current of 120 milliamperes approximately. The primary coil 253 of the transformer 249 is connected in series with a switch 255 across the terminals of the supply 251 whilst the secondary coil 257 of the transformer which is adapted to yield a secondary voltage of 215 volts R.M.S. is connected in series with the voltage doubler unit 247 which is of well known form and comprises a pair of rectifiers 259 and a pair of capacitors 261 each having a capacitance of 16 microfarads. The voltage doubler unit 247 is adapted to establish across the pair of capacitors 261 a unidirectional output voltage of value less than twice the peak voltage developed across the secondary coil 257 of the transformer by an amount which depends upon and increases with increase of the current drawn from the voltage doubler unit. The output voltage from the voltage doubler unit 247 is applied to the series combination of the resistor 245 and capacitor 241 to effect

5 charging of the capacitor 241, the latter being periodically discharged across the electrodes of the sparking plug 1 through operation of the switching device 243. Thus the series combination of the plug 1 and switching device 243 constitutes a discharge circuit for the capacitor 241.

10 The switching device 243 comprises a four lobe cam 263 keyed to the shaft 265 of an electric motor (not shown) which is arranged to be energised upon closure of the switch 255. Associated with the cam 263 is a pivotally mounted follower 267 to which is connected a contact arm 269 provided with an electrical contact element 271, the element 271 being biased towards contact with a fixed contact element 273 by means of a leaf spring 275. The contact element 271 is in electrical connection with the electrode 3 of the plug 1 whilst the element 273 is in electrical connection with the negative side of the capacitor 241.

15 When forward movement of the plug 1 is initiated, during operation of the burner 131, by supplying air to the cylinder 225, the switch 255 is closed and the motor associated with the cam 263 is simultaneously energised. Upon rotation of the cam 263 the contact elements 271 and 273 are closed four times per second to provide, at the same rate, discharges of the capacitor 241 across the annular surface 13 of the mica tube 7 between the electrodes 3 and 5 of the sparking plug 1. Upon rearward movement of the plug 1, the switch 255 is opened and the motor associated with the cam 263 is simultaneously de-energised, whereupon sparking of the plug 1 is terminated.

20 What I claim is:

1. An electric spark igniter, for use with a fluent fuel burner and arranged for projection and retraction to and from an operative position, said igniter comprising, in combination, a relatively elongated inner electrode; a relatively elongated tubular outer electrode surrounding said inner electrode and radially spaced substantially therefrom throughout the major portion of the length of said tubular electrode to provide rigidity for the igniter; said electrodes being elongated in the direction of such projection and retraction and the sparking end of the inner electrode projecting a short distance beyond the sparking end of the outer electrode; and insulation material disposed between said inner and outer electrodes and including an insulating sleeve having an outer end flush with the sparking end of the outer electrode to provide an annular surface of insulating material traversed by spark discharges between the electrodes when the igniter is energized; said outer electrode being reduced in diameter adjacent its sparking end to compress the outer portion of said sleeve between said electrodes; the length of said sleeve being a minor fraction of the length of said electrodes but at least equal to the length of the reduced portion of said outer electrode.

2. An igniter as claimed in claim 1, wherein the outer electrode comprises a length of tubing of smaller diameter than that of a reciprocable tubular holder from which the outer electrode projects.

3. An igniter as claimed in claim 2, wherein the spark igniter is readily replaceable in relation to the reciprocable holder.

4. An igniter as claimed in claim 2, wherein the spark igniter is mounted within and projects from the holder and the inner electrode projects rearwardly beyond the outer electrode in order to engage a resilient electrical terminal device associated with the holder.

5. An igniter as claimed in claim 1, wherein the inner electrode is in the form of a slender rod and the outer electrode comprises a length of tubing.

6. An igniter as claimed in claim 1, wherein the insulation material is erodible by spark discharges, the outer electrode is adapted to operate at an electric potential which is positive with respect to that of the inner electrode and the thickness of the outer electrode, at least at the

forward end thereof, is such as will cause erosion of that electrode, during operation of the spark igniter, at a rate substantially equal to that at which the insulation material is eroded.
